ARC INDICATOR SYSTEM FOR PROJECTION LAMPS

Neal Brenkert, Detroit, Mich.

Application January 29, 1937, Serial No. 123,026

2 Claims. (Cl. 176—51)

The present invention pertains to a novel arc indicator system for projection lamps, particularly of the type employing carbon electrodes.

Lamps of earlier construction are equipped with an arc indicator screen mounted on the top of the lamp, and in the transverse vertical plane of the arc to maintain the image upright. While the arc may be satisfactorily projected on the screen, the position of the screen is such that it frequently cannot be seen conveniently by the operator. In order to see the image of the arc on the screen, he is obliged to move his body considerably to one side or the other of the axis of the machine, thereby taking his attention from other operations that must be simultaneously performed at the rear end of the machine. This is particularly annoying to operators of short stature, and as a result, the operator often fits an elevated bracket upon the lamp housing to hold the screen, or causes the arc image to be projected on the ceiling of the projection room. Either of these expedients is obviously awkward and unsatisfactory, as will be recognized by those skilled in the art.

One of the objects of the present invention is to mount the screen in a more convenient position, offset from the transverse vertical plane of the arc, and at the same time project an upright image on the screen. The screen is so positioned that the image may conveniently be seen by the operator while he is adjusting the controls at the rear end of the machine, without introducing any awkwardness in the mounting of the screen or its supporting parts. Such offset position of the screen, which may be either forward or rearward, avoids interference with the chimney that stands directly over the arc.

Another object of this invention consists in providing a novel and unique mirror arrangement for imaging the arc in the desired upright position, as will appear more fully hereinafter.

The invention is fully disclosed by way of example by the following description and the accompanying drawings, in which

Figure 1 is a side elevation of a lamp housing equipped according to the invention;

Figure 2 is a rear end view thereof;

Figure 3 is a section on the line 3—3 of Figure 1;

Figure 4 is a section on the line 4—4 of Figure 2;

Figure 5 is a section on the line 5—5 of Figure 4, and

Figure 6 is a section on the line 6—6 of Figure 4.

Reference to these views will now be made by use of like characters that are employed to designate corresponding parts throughout.

In Figures 1 and 2 is shown a lamp housing 1 of known design except for the particulars specifically described herein. From the rear wall of the housing extends a protuberance 2 for containing certain parts of the feeding mechanism which may be adjusted by hand at the knobs 3.

The housing contains a pair of electrodes 4 and 5 that form an arc 6. To a side wall of the housing, at some distance above the arc and above the door 7, is secured a bracket 8 (Figure 3) formed with a mirror frame 9. In the frame is mounted a mirror 10 held in position by a split ring 11.

From the bracket 9 a lens tube 12 extends through a hole 13 formed in the housing 1. This tube is positioned so that its axis intersects the arc 6 as may be seen more clearly in Figures 1 and 2. The tube 12 contains a spacer tube 14. At the ends are plano-convex lenses 15 facing one another. The upper lens 15 bears against a coil spring 16 mounted in the upper end of the tube 12. A screw tube 17 is threaded in the lower end 25 of the tube 12 and bears against the lower lens 15, whereby both lenses and the spacer tube 14 may be adjusted as a unit in the tube 12. The adjustment is secured by means of a lock nut 18 threaded on the screw tube 17 and bearing against the lower end of tube 12.

At a higher point on the lamp housing, and on the same side, is mounted another mirror by the means now to be described. At this point is formed an ear 19 on the housing near the end 35 wall thereof. Through the ear is passed a headless bolt 20 having an acorn nut 21 screwed on its outer end and bearing against the ear 19.

On the other end of the bolt is loosely mounted a collar 22. Through the collar and the bolt is 40 passed a right-angled pin 23 for carrying the remaining mirror frame as will presently be described. It may be seen, however, that tightening of the nut 21 tends to draw the bolt through the collar 22, thereby binding the pin 23 by a 45 shearing action between the bolt and the collar.

As already indicated, the pin 23 serves to support another mirror frame 24, passing through a lug 25 thereon. A mirror 26 is mounted in the frame 24 and held by a spring ring 27 as shown in 50 Figure 4. The mirror 26 is positioned to receive light from the mirror 10 and project it upon an indicator screen as will now be described.

For supporting this screen, a frame 28 is secured to the rear wall of the lamp housing and 55

at an elevation preferably slightly higher than the mirror frame 24. The rear end of the chimney 29 has been found to be a suitable place for mounting the frame 28.

5 The screen 30 mounted in the frame 28 is of suitable material, such as frosted glass, so that the image projected thereon from mirror 26 may be seen from either side. The screen has gauge lines 31 on each side, the proper adjustment of the 10 arc producing an image having a certain relation to these lines, known to the operator and substantially as illustrated in Figure 1.

15 Directly above the screen, a frame 28 is formed with a shield or visor 32 extending in both directions. This member shields the screen from overhead light and shadows, thereby rendering the 20 image more distinct and readily visible.

25 With the screen in the position described, the image may be seen by the operator without taking his attention from the controls 3. Only a slight movement of the head is necessary, whereas a screen mounted upon the chimney as formerly requires the operator to stoop forward and swing his body sidewise. These movements are so 30 awkward that the operator frequently prefers to discard the screen so mounted and provide some other means, usually improvised, for showing the image.

35 The screen mounted in the position herein described, although projecting from the housing, is disposed in the angle between the rear wall of the housing and the top of the protuberance 3 and is shielded within this angle so that it does not impede the movements of the operator about 40 the machine.

45 In order that the arc 6 be projected rearwardly to the screen, both mirrors 10 and 26 are tilted somewhat rearwardly as illustrated. The mirror 10 nearer to the arc requires no adjustment after 50 assembly and its frame 9 is held in a fixed position with the bracket 8. The image of the arc 6 is projected by mirrors to the screen 30 along the arrows shown in Figures 1 and 2.

55 Slight but accurate adjustments of the upper mirror 26 may be necessary. The mounting described permits adjustment in three directions. The assembly is rotatable towards and away from the lamp housing by turning the bolt 20 on its axis before tightening the nut 21. Another adjustment, lengthwise of the housing, is made by 60 turning the pin 23 in the collar 22 and bolt 20 before tightening the nut 21. The third adjustment, perpendicular to the bolt 20, is made by shifting the pin 23 in the bolt 20 and collar 22 before tightening the nut 21.

65 The mirror frame 24 is fixed to the pin 23 by any suitable means such as a pin 33 driven through the pin 23 and lug 25 of the frame.

70 It is important that the image be shown upright on the screen. Heretofore there has been no difficulty in this connection, as the screen was positioned in the transverse vertical plane of the arc, and it was only necessary to mount the mirrors perpendicular to said plane with their 75 centers in said plane. In the present construction, a more particular arrangement of the mirrors is necessary to project the arc rearward to the screen and yet maintain the image in an upright position.

75 The adjustments of the mirrors will vary according to the size of the lamp housing and relative position of the screen and arc, but certain general requirements are to be observed. The lower mirror 10 is positioned so that its center lies

approximately in the transverse vertical plane of the arc, and the upper mirror 26 is offset from this plane in the direction towards the screen 30, or along the longitudinal axis of the housing. It has previously been customary in the art, where 5 two mirrors were used, to mount the upper mirror directly over the lower mirror, but in the offset position of the screen 30 relative to the transverse vertical plane of the arc, it was found that such an arrangement of mirrors caused the image of 10 the arc to be other than upright on the screen. The offset position of the upper mirror 26 and the angular adjustments of both mirrors, presently to be described, results in an upright image on the screen and are therefore important in this 15 invention.

15 The lower mirror 10 is tilted away from the vertical axial plane of the housing to reflect upwardly and is also turned on a vertical axis towards the upper mirror 26 to reflect into the 20 same. Similarly, the upper mirror 26 is positioned at the proper angle to the transverse vertical plane of the arc to reflect to the level of the screen 30 and is further turned on a vertical axis to throw a beam of light laterally upon the 25 screen 30.

25 In the scale of dimensions illustrated in the drawings, the following angular adjustments of the mirrors result in an upright image on the 30 screen 30: the lower mirror 10 is tilted $22\frac{1}{2}^\circ$ away from the vertical axial plane of the housing and is turned on a vertical axis to an angle of 17° 35 towards the upper mirror 26. The adjustment of the upper mirror 26 then follows as a matter of course, as it is only necessary that this mirror be focused upon the screen 30. Thereupon, an upright image of the arc is produced as a consequence of the mounting of the mirror 10 previously described. Precise adjustment of the mirror 26 is obtained by turning the bolt 20 and 40 sliding and turning the pin 23 in the manner already set forth.

45 Although a specific embodiment of the invention has been illustrated and described, it will be understood that various alterations in the 50 details of construction may be made without departing from the scope of the invention, as indicated by the appended claims.

55 What I claim is:

1. In combination with a projection lamp housing, an image indicator screen mounted on the rear wall thereof, a mirror mounted on said housing and positioned to receive light from the interior of said housing, an ear formed on said housing between said mirror and screen, a bolt 50 in said ear, and another mirror supported by said bolt and positioned to reflect light from the first mirror to said screen, a collar loose on said bolt, a pin passed through said collar and bolt, and means for tightening said bolt in said ear, and 55 another mirror supported by said pin and positioned to reflect light from the first mirror to said screen.

2. In combination with a projection lamp housing, an image indicator screen mounted on the rear wall thereof, a mirror mounted on said housing and positioned to receive light from the interior of said housing, an ear formed on said housing between said mirror and screen, a bolt 60 in said ear, a pin lengthwise rotatably adjustable 65 in said bolt, and another mirror carried by said pin and positioned to reflect light from the first mirror to said screen.

70 NEAL BRENKERT.
